GUIDE FOR CORRECTING TYPEWRITTEN COPY

Ronald D. Schoesler, P.O. Box 111,
Pullman, Wash. 99163

Filed Jan. 30, 1967, Ser. No. 5,611

Term of patent 14 years

(Cl. D52—6)

Fig. 3.

Fig. 2.

Fig. 1.

FIG. 1 is a plan view of the guide showing my new design;

FIG. 2 is a side edge view of the guide; and

FIG. 3 is an end edge view of the guide.

The side of the guide which is the reverse of that shown in FIG. 1 is conventionally plain.

I claim:

The ornamental design for a guide for correcting typewritten copy, as shown and described.
